J. MULROY

PORATABLE OIL BURNER AND TORCH

Filed Sept. 18, 1925

UNITED STATES PATENT OFFICE.

JOHN MULROY, OF JERSEY CITY, NEW JERSEY.

PORTABLE OIL BURNER AND TORCH.

Application filed September 18, 1925. Serial No. 57,217.

To all whom it may concern:

Be it known that I, JOHN MULROY, a citizen of the United States, and a resident of Jersey City, county of Hudson, and State of New Jersey, have invented a new and Improved Portable Oil Burner and Torch, of which the following is a full, clear, and exact description.

This invention relates to a heating device especially adapted for melting snow.

An object of the invention is to provide a simple and efficient device which is readily portable for directing flames to melt snow, especially on railroads in connection with switches.

A further object is to provide a simple and efficient device which is provided with suitable supporting means so that it can be set up to act as a flare on railroads when work at night has to be performed.

The invention is illustrated in the drawings of which Figure 1 is a vertical section through the device;

Figure 2 is a section on the line 2—2 of Figure 1;

Figure 3 is an elevation of the device set up for use as a flare.

The form of the invention shown in the drawings is a preferred form, although it is understood that modifications in the construction and arrangement of the parts and in the character of the materials used may be adopted without departing from the spirit of the invention as set forth in the appended claims.

The invention in its general aspect comprises a nozzle in the form of a tubular member having a perforated opening. A funnel shaped member is associated with the end of the nozzle to confine and direct the flames issuing from the nozzle. Within the tubular nozzle is a pipe the end of which is disposed near the end of the nozzle for the purpose of projecting air under pressure toward the end of the nozzle. Oil under pressure is introduced into the nozzle at a point to the rear of the air pipe and is drawn toward the end of the nozzle by the suction of the air with which it becomes mixed adjacent the end of the nozzle. This mixing of the air and the oil results in a highly inflammable mixture which when ignited and forced out under pressure, will form a flame of considerable length, which is directed and con-

trolled by the funnel on the end of the nozzle. The pipes conveying the air and oil are of preferably short length and can be connected to flexible hose so that the device can be carried around from point to point at any desired distance from the source of air and oil supply.

The device is provided with a tripod support which is readily collapsible when not in use and is capable when in use of holding the device inverted so that the flame can be directed upwardly to act as a flare to illuminate the vicinity at night.

In the drawings the preferred form of the invention includes a tubular nozzle member 10 the lower end of which is provided with a perforated cap 11. Around the lower end of the nozzle member a cup-shaped support 12 is mounted and provided with air holes 13. This member 12 supports a funnel 14.

Within the nozzle member is disposed an air pipe 15 supported in the nozzle member by a cap 16. The air pipe has a valve 17 therein. The lower end 18 of the air pipe is disposed a short distance from the end of the nozzle member. A T-shaped head 19 embraces the middle portion of the nozzle member and an oil pipe 20 is connected thereto. A valve 21 is disposed in the oil pipe.

In order to support the device in an inverted position for use as a flare, I attach to the head 19 a plurality of tripod legs 22 which in turn are connected by links 23 with a sleeve 24 slidable along the nozzle member. As shown in Figure 3 the legs 22 will support the device. By sliding the sleeve 24 upward the legs may be collapsed to lie along the piping when not in use.

In the operation of the device I supply compressed air and oil under pressure through the pipes mentioned and by the valves can determine the proper mixture of the oil and the air. As the air issues from the lower end of the pipe 15 it causes a suction in the nozzle member which draws the oil into the nozzle member in a finely divided condition and thoroughly mixes with the oil in the nozzle member just below the end of the pipe 15. The mixture passes through the perforations 11 and is ignited forming a flame which is confined and directed by the funnel member 14. This flame can be directed to melt the snow or ice

around switches and the like or may be used as a flare when the device is disposed as shown in Figure 3.

What I claim is:—

- 5 1. A portable oil burner and torch which comprises a nozzle member having a perforated end, a funnel-shaped flame and heat controlling element mounted on said end and projecting therebeyond, said funnel-shaped element having air passages in its rear wall around the end of the nozzle, an air pipe extending into the nozzle member to a point adjacent the perforated end, and an oil pipe opening into the nozzle member at a point midway the length thereof, the oil and air being mixed within the nozzle member at a point just beyond the end of the air pipe.
- 10
- 15

2. A portable oil burner and torch which comprises a nozzle member having a perforated end, a funnel-shaped flame on said end controlling element mounted on said end and projecting therebeyond, said funnel-shaped element having air passages in its rear wall around the end of the nozzle, an air pipe extending into the nozzle member to a point adjacent the perforated end, and an oil pipe opening into the nozzle member at a point midway the length thereof, the oil and air being mixed within the nozzle member at a point just beyond the end of the air pipe, and a collapsible tripod supporting means connected to the nozzle member and adapted to support it in an inverted position when desired.

JOHN MULROY.
